UNITED STATES PATENT OFFICE.

WILLIAM FULLARD, [OF PLAINFIELD, NEW JERSEY, AND CHARLES M. DONHAM, OF PORTLAND, MAINE.

DEVICE FOR REMOVING STATIC ELECTRICITY FROM STOCK.

No. 854,413.

Specification of Letters Patent.

Patented May 21, 1907.

Application filed June 5, 1906. Serial No. 320,283.

To all whom it may concern:

Be it known that we, WILLIAM FULLARD, a citizen of the United States, residing at Plainfield, county of Union, State of New Jersey, and CHARLES M. DONHAM, a citizen of the United States, residing at Portland, in the county of Cumberland, State of Maine, have invented a new and useful Device for Removing Static Electricity from Stock, of which the following is a specification.

Our invention relates to a new and useful apparatus for removing static electricity from paper, cloth or other material, or stock, which is fed to a machine and consists in applying heated air at a suitable time to the paper, cloth, etc. in its passage to or through the machine.

It further consists of novel details of construction all as will be hereinafter set forth.

Figure 1 represents a partial elevation and partial sectional view of the apparatus embodying our invention, showing a portion of a machine in connection therewith. Fig. 2 represents a side elevation of a portion, of the device showing the same as applied to sheets of paper or other material. Figs. 3 and 4 represent side elevations of portions of the device, showing its application to a continuous roll of material, or to stacks of sheets respectively.

Similar numerals of reference indicate corresponding parts in the figures.

Referring to the drawings—it is well known that static electricity is present in paper, cloth, silk, cotton, etc., and in fact most any stock which is fed to machines for various purposes; and it is readily noticeable in paper for example, where two sheets will adhere together, when an effort is made to remove the upper or lower sheet and the loss due to this electricity is very considerable and is not dependent upon the weather or temperature.

We have shown in the drawing, a form of apparatus for overcoming or removing this static electricity and while we have shown certain features it will be evident that changes may be made therein, in order to accomplish the same result. We have also illustrated only a portion of a machine which may be a printing machine or otherwise, it being understood that the apparatus is adapted for use for any kind of machines where

stock is fed thereto and where static electricity may exist.

In the drawings 1 designates a tank which is adapted to contain air and in which is situated a steam coil 2 which is in connection with a suitable source of steam supply. Beneath the chamber or tank is a burner 3 which is adapted to assist in heating air in the tank and in the drawings we have shown the sides of the tank as extending below the burner as at 4 in order to properly protect the same, although it will be understood that the burner may be situated exterior to the tank or around the sides thereof as deemed most expedient.

5 designates an air compressor which in the present instance is shown integral with the tank 1, although it will be understood that the same may be a separate casing and may be attached to the tank 1 in any suitable or desired manner, said tank 1 having an opening or passage 6 forming a communication between the interior of the said tank 1 and the air compressor 5. 7 designates a piston in said air compressor which is connected with the crank shaft 8, the latter in this instance being supported on the standards or journals 9 carried by the air compressor 5 and said crank shaft 8 having suitable power imparted thereto through the pulleys 10 in any desired manner.

Leading from the interior of the air tank 1 is a main air pipe 11 which has the extension 12 connected therewith, the same extending any distance as desired and having the pipe 13 in communication therewith at a suitable point which carries the distributing air pipe 14 the latter in the present instance extending horizontally and being provided with the openings 15 in its lower face a suitable valve 16 controlling said distributing air pipe 14.

It will be understood that any desired number of these distributing pipes may be employed, it only being necessary to have them communicate with the main air pipe extension 12, so that said distributing pipe 14 may be located above any desired number of machines and all of said distributing pipes being supplied from the same air tank if desired.

In the drawings we have shown a portion of a printing press for example which consists of the frame 17 carrying the rolls 18.

over which the stock is passed in its passage to the press and we have shown a sheet of paper 19 passed over said roll and directly beneath the discharge openings 15 in the air distributing pipe 14, it being seen that in this manner the entire surface of the paper receives the hot air which is forced from the air tank 1 by the movement of the piston 7 through the pipes 11 and 12 and the pipe 13 to the distributing pipe 14, it being understood that the valve 16 is properly operated to permit this action. The air in the tank 1 can be heated through by the steam pipes 2 or the burner 3 or by both in order to supply the desired temperature to the air.

In Fig. 3 I have shown a roll 20 of stock such as paper or the like, said stock receiving the discharge of hot air from the pipe 14 in its passage through the machine and before passing between the rollers 21.

In Fig. 4, we show the device as applied to stacks of paper in the form of sheets. The distributing pipe 14 is shown as being situated over or around the stacks in order to direct the hot air against the upper sheet or sides of the stack before it is removed from the stack in its passage through the machine. It will be seen therefore that the static electricity can be removed from the stock at any suitable time, either before it is set to the machine, or as it is being fed, or in its passage through the machine.

Having thus described our invention, what we claim as new and desire to secure by Letters Patent is:—

1. In a device of the character described, a hot air tank and means for discharging the

heated pure atmospheric air over the surface of the stock as it is fed to or through the machine.

2. In a device of the character described, a tank, means for compressing the air in said tank and for heating the air therein, and means for discharging the air against the stock as it is fed to or through a machine.

3. In a device of the character described, a tank, means whereby the atmospheric air is heated without being mixed with the products of combustion, means for forcing the air into and from said air tank and a distributing pipe in communication with said air tank for directing the hot air downwardly against the stock.

4. In a device of the character described, a tank, heating devices therefor, means for forcing air into and from said air tank, a distributing pipe in communication with said air tank for directing the heated pure atmospheric air against the stock, and means for controlling said distributing means.

5. In a device of the character described, an air tank, means for heating air therein, a pipe leading from the exterior of said tank, an air compressor for forcing air into said tank, and through said pipe, an offset pipe connecting said main pipe, an air distributing pipe having openings therein for discharging the hot air against the stock, and means for controlling said distributing pipe.

WILLIAM FULLARD.
